UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

MATERIAL-ELEVATING APPARATUS.

Application filed September 29, 1922. Serial No. 591,285.

To all whom it may concern:

Be it known that I, BARTON S. SNOW, a citizen of the United States, residing at Batavia, in the county of Kane and State 5 of Illinois, have invented a new and useful Improvement in Material-Elevating Apparatus, of which the following is a specification.

My invention relates to apparatus of the 10 general type commonly used for elevating material such as, for example, coal, from a hopper into which the material is dumped from railway cars located on tracks above the hopper, into a storage bin above the 15 tracks, from which the material is permitted to discharge as, for example, into the tenders of locomotives, this type of apparatus comprising a vertically-operating bucket or skip for elevating the material 20 into the uppermost hopper, and power-operated cable means for operating the bucket.

My primary object, generally stated, is 25 to provide a novel, simple and positively-operating apparatus of the character stated which will operate, the more satisfactorily to perform, the functions for which such apparatus is provided.

Referring to the accompanying drawings: 30 Figure 1 is an enlarged elevational view of the lower part of apparatus embodying my invention, with certain parts sectioned, this view showing, by full lines, the position occupied by the parts cooperating with 35 the bucket when the bucket is at a certain point intermediate the limits of its travel, and by dotted lines the positions assumed by these parts when the bucket is in filling position. Figure 2 is a section taken at 40 the line 2 on Fig. 1 and viewed in the direction of the arrow. Figure 3 is a plan sectional view taken at the irregular line 3—3 on Fig. 1 and viewed in the direction of the arrows. Figure 4 is a section taken 45 at the line 4 on Fig. 1 and viewed in the direction of the arrows; and Figure 5, a broken view in sectional elevation of a portion of the apparatus showing the measuring receptacle forming a part thereof, in 50 the position it occupies for discharging its contents into the bucket.

The apparatus shown comprises a pit structure, represented generally at 6, which extends below the level at which the tracks,

represented at 7 and on which the cars containing the material to be elevated are run, 55 extend, this pit being shown as opening into a hopper located at the upper portion of the pit. The tracks 7 are shown as extending across the top of the hopper 8, and 60 the opening through which the hopper communicates with the pit and which forms the outlet of the hopper at the lower end of the latter is represented at 9.

Extending at its lower end into the pit 65 6, and rising therefrom to any desired height, is a superstructure, the lower portion only of which is shown. By way of example and in accordance with common practice, this superstructure may comprise 70 a hopper, not shown, for receiving the material elevated from the hopper 8, as herein-after described, and equipped with means (not shown) for controlling the discharge of the material from the uppermost hopper 75 as desired, as for example into the tenders of locomotives located below the uppermost hopper. The framework referred to provides the support and guiding means for a vertically movable bucket or skip, represented at 10 and provided for the purpose of elevating material from the hopper 8 to a position in which it discharges into 80 the uppermost hopper. This last-referred-to portion of the framework is provided at 85 its opposite sides with pairs of vertical bars 11 and 12 spaced apart to provide guides for the bucket 10, the latter to this end being provided with a cross-bar and studs 13 and 14, respectively, which extend into 90 the channels 15 provided between the bars referred to. The bucket 10 is of a construction commonly provided in apparatus of this general type, this bucket being provided with a bail 16 pivotally connected 95 at its lower end with the under side of the bucket.

The bucket 10 is raised and lowered in the guideways referred to, in any desirable manner, as is well understood in the art, 100 it being common practice to provide cable means which are represented in the drawing at 17 and are shown as connected with the upper end of the bail 16, these cable means being connected with windlass mechanism not shown. Where a single bucket 10 is employed it is preferred that a counterweight (not shown) be provided 105

for cooperation therewith to partially counterbalance the loaded bucket. Where, however, a pair of the buckets are employed which operate in opposite directions, in accordance with arrangements commonly provided, the counterweight may or may not be dispensed with, as desired.

Cooperating with the hopper 8, and located at the outlet 9 thereof, is mechanism 10 for receiving a charge from this hopper and dumping the same into the bucket 10 when the latter is in the dotted position shown in Fig. 1, a description of this mechanism being as follows. The mechanism referred to comprises a charge-receiving receptacle 18 which may be of general rectangular form with its top open, the lower portion of the front wall of the receptacle containing a discharge opening represented at 19. The receptacle 18 is provided at its lower end with a pair of arc-shaped rocker bars 20 which are located at opposite sides of the receptacle 18 and are rigidly secured thereto, whereby these rocker bars are spaced apart as shown. The bars 20 are preferably of angle shape in cross-section, one of the flanges 21 of each of which, and at which the receptacle is supported on a track hereinafter referred to, containing a series of equidistantly-shaped openings 22 therein. The receptacle 18, by reason of the provision of the rockers 20, is of a type adapting it to be rocked or rolled along a support from a position in which it receives a charge from the hopper 8 through the discharge 9, this position being represented by full lines in Fig. 1, to a position in which the contents thereof discharges through the outlet 19, this position being represented by dotted lines in said figure. The track forming the support for the receptacle 18, and upon which the latter rocks, is shown as formed of a pair of rails 23 extending parallel with each other in spaced-apart relation, these rails being shown as supported upon a frame 24 rigidly secured at one end in a wall of the pit 6 and projecting therefrom into the pit toward the path of movement of the bucket 10, the framework referred to being shown as formed of a pair of beams 25 extending in parallel relation and connected together at their outer ends by a cross-bar 26. The rails 23 are spaced apart the same distance as the rockers 20 and each is provided with a series of upwardly-extending pins 27 equidistantly spaced apart the same distance as the openings 22, the parts just referred to being so constructed and arranged as shown that in the rolling of the receptacle 18 upon the track, the pins 27 are caused to successively extend into the openings 22, thereby operating to prevent lateral displacement of the receptacle 18 upon the track, without presenting any obstruction to the rocking of the receptacle on the track. Cooperating

with the outlet 19 of the receptacle is an apron device which serves primarily as a means for directing the contents of the receptacle 18 into the bucket 10 when the latter is in filling position. The apron device referred to, and which is represented generally at 28, is of general U-shape in cross-section, it being pivotally connected with the receptacle 18, as represented at 29, in straddling position relative to the latter, this apron device being weighted, as represented at 30, for a purpose hereinafter explained. The operating mechanism for the receptacle 18, in accordance with the illustrated embodiment of my invention, comprises cables 31 connected intermediate their ends with the receptacle 18 at opposite sides of the latter, as represented at 32. The corresponding ends of each of the cables extend over sheaves 33 journaled on a stationary part of the structure and thence extend downwardly and are connected at their lowermost extremities with a cross-bar 34 which is movable up and down in guideways 35 located at opposite sides of the pit and formed by the uprights 11 and upright bars 36 located closely adjacent thereto, but spaced therefrom. The cross-bar 34 extends directly beneath the bucket 10 and into a position in which the latter in the final position of its lowering movement to filling position, engage this cross-bar and forces it downwardly as, and for the purposes, hereinafter described. The other corresponding ends of the cables 31 extend around sheaves 37 journaled on a stationary part of the structure at opposite sides of the receptacle 18, these ends of the cables thence extending forwardly toward the bucket and over sheaves 38 journaled at opposite sides of the bucket on a stationary part of the structure, the lower extremities of these ends of the cables being connected, respectively, with counterweights 39 which exert a force tending to rock the receptacle 18 toward the left in Fig. 1.

Means, cooperating with the receptacle 18, are provided for closing the hopper outlet 9 in the movement of the receptacle 18 to bucket-filling position, to avoid discharge of material from the bin into the pit, these means comprising a gate device, represented generally at 40 and shown as in the form of a framework formed of the side members 41 which are pivoted at their forward ends on a bar 42 located below the framework 24 and extending upwardly between the bars 25, and a curved cross-plate 43 connected with the opposite ends of the arms 41 and of a width preferably slightly greater than the width of the opening 9 in alignment with which it extends. The gate device 40 which is thus a pivotally-supported device, cooperates with means whereby it is caused to automatically move into a position in which it closes the

outlet 9 to the discharge of material there-through, in the moving of the receptacle 18 toward the dotted position shown in Fig. 1 and into a position in which it opens the outlet 9 to the flow of material therefrom and into the receptacle 18, in the movement of the latter to the full line position shown in this figure, these means comprising a pair of weights 44 which are connected with the lower ends of cables 45 which extend over sheaves 46 journaled on a stationary portion of the structure at opposite sides of the pit, and thence extend downwardly to the gate structure 40 connecting with the latter at opposite sides thereof, as represented at 47, the weights 44 thus operating to maintain the gate device 40 in engagement with the receptacle 18 within the limits represented by the full line and dotted line positions of the gate device 40 in Fig. 1, regardless of the position occupied by the receptacle 18.

The operation of the apparatus is as follows: The normal position occupied by the mechanism which delivers the material from the hopper 8 to the bucket 10, is that represented by full lines in Fig. 1 wherein the receptacle 18 is in communication at its open, upper, end with the hopper 8 through the outlet 9, in which position of the receptacle the latter is charged with a predetermined amount of material from the hopper, the gate device 40 being held in the depressed condition by engagement with the receptacle 18. As the bucket 10 in descending nears the limit of its downward movement, it engages the crossbar 34 with the result of drawing on the cables 31, whereby the receptacle 18 is rocked on the track 23 from the full line position, represented in Fig. 1, to the right in this figure, and by the time the bucket 10 has reached the dotted position shown in Fig. 1, the receptacle 18 will have been moved to the dotted position shown in this figure during which movement the apron device 28 swings on the receptacle 18 from the full line position represented in Fig. 1 to the dotted line position represented in this figure in which it extends at its lower edge over the bucket 10 and directs into the latter the material which discharges from the receptacle 18 through its outlet 19. It will be understood that in the rolling of the receptacle 18 to the dotted line position shown in Fig. 1, the gate device 40 is caused to automatically move to a position in which it closes the hopper outlet 9. In the rising movement of the filled bucket 10, the weights 39 are permitted to operate and the receptacle 18 rocks from the dotted position shown in Fig. 1 to the full line position shown therein, the gate device 40 in this movement being forced against the action of the weights 45 to the full line position shown in this figure. As the apron device 28 extends, in the lowermost position of the bucket, over

the upper edge of the latter, the bucket, in rising, rocks this apron upon its pivot 29 to a position wherein the weighted portions 30 of the apron device cause the latter to close the opening 19 of the receptacle 18. 70

It is preferred that the apparatus be so constructed and arranged that the receptacle 18 will tend to roll, at all times, to the left in Fig. 1, though such an arrangement is not necessary in so far as certain of the features 75 of my invention are concerned.

It will be understood that the weights 39 should be sufficiently heavy not only to insure the return of the receptacle 18 to the full line position shown in Fig. 1, but also 80 to actuate the gate device 40 to the full line position shown in this figure, against the action of the weights 44. The weights 39 are shown as provided solely for the purpose just stated. However, other means may be provided for this purpose, as for example where the apparatus involves a counter-weight for the bucket, moving in opposite directions relative to the latter, such counter-weight may be caused to perform in addition 85 to its usual function, that performed by the weights 39.

While I have illustrated and described a particular construction embodying my invention, I do not wish to be understood as 90 intending to limit it thereto, as the same may be variously modified and altered without departing from the spirit of my invention.

What I claim as new and desire to secure by Letters Patent is— 100

1. Material elevating apparatus, comprising in combination, a hopper, a bucket for elevating material located adjacent said hopper, a support, a receptacle engaging said support for receiving material from said hopper for discharge into said bucket, said receptacle being between said hopper and bucket and bodily movable along said support from said hopper toward said bucket and tiltable into a position for discharging 105 its contents into said bucket.

2. Material elevating apparatus, comprising in combination, a hopper, a bucket for elevating material located adjacent said hopper, a support, a receptacle for receiving material from said hopper for discharge into said bucket, said receptacle being between said hopper and bucket, and having a curved supporting surface at which it is supported on, and bodily rollable along, 110 said support from a position in which it receives a charge from said hopper to a position in which it discharges into said bucket.

3. Material elevating apparatus, comprising in combination, a hopper, a bucket for elevating material located adjacent said hopper, a support, a receptacle engaging said support for receiving material from 115 said hopper for discharge into said bucket,

- 5 said receptacle being between said hopper and bucket and bodily movable along said support from said hopper toward said bucket and tilted into a position for discharging its contents into said bucket, and means operating in timed relation to the movement of said bucket for moving said receptacle into a position in which its contents may be discharged into the bucket.
- 10 4. Material-elevating apparatus comprising, in combination, a hopper, a bucket for elevating the material, a support, a receptacle for receiving material from said hopper, for discharge into said bucket, said receptacle being mounted on said support to be bodily movable along the latter toward and away from said hopper and tilted into material-discharging position, and means movably supported on said receptacle for directing the material therefrom.
- 15 5. Material-elevating apparatus comprising, in combination, a hopper, a bucket for elevating the material, a support, a receptacle for receiving material from said hopper, for discharge into said bucket, said receptacle being mounted on said hopper to be bodily movable along the latter toward and away from said hopper and tilted into material-discharging position, and means movably supported on said receptacle for
- 20 30 35 40 45 50 55 60 65

8. Material-elevating apparatus comprising, in combination, a hopper, a bucket for elevating the material, a support, a receptacle for receiving material from said hopper, for discharge into said bucket, said

receptacle being mounted on said hopper to be bodily movable along the latter toward and away from said hopper and tilted into material-discharging position, means operated by said bucket for moving said receptacle into discharging position, and mechanism yieldingly resisting movement of said receptacle out of filling position and operative to return said receptacle to filling position.

9. Material-elevating apparatus comprising, in combination, a hopper, a bucket for elevating the material, a support, a receptacle for receiving material from said hopper, for discharge into said bucket, said receptacle being mounted on said support to be bodily movable thereon toward and away from said hopper and tilted into material-discharging position, cable and weight mechanism for moving said receptacle toward receptacle-filling position, and means operated by said bucket for moving said receptacle toward receptacle-discharging position.

10. Material-elevating apparatus comprising, in combination, a hopper, a bucket for elevating the material, a support, a receptacle for receiving material from said hopper, for discharge into said bucket, said receptacle being mounted on said support to be bodily movable along the latter toward and away from said hopper and tilted into material-discharging position, means movably supported on said receptacle for directing the material from said receptacle into said bucket, and means operated by said bucket for actuating said receptacle, said first-named means being operated toward receptacle-closing position by said bucket.

11. In material-elevating apparatus, the combination of a hopper, a bucket for elevating the material, a support, a receptacle for receiving material from said hopper, said receptacle having a curved supporting surface at which it is supported on, and bodily rollable along, said support from material-receiving to material-discharging position, means for closing the outlet of said hopper, and means operated by said bucket for actuating said receptacle.

12. Material-elevating apparatus comprising, in combination, a hopper, a bucket for elevating the material, a support, a receptacle for receiving material from said hopper, for discharge into said bucket, said receptacle having a curved supporting surface at which it is supported on, and bodily rollable along, said support, and means movably supported on said receptacle for directing the material therefrom.

13. Material-elevating apparatus comprising, in combination, a hopper, a bucket for elevating the material, a support, a receptacle for receiving material from said hopper, for discharge into said bucket, said receptacle having a curved supporting sur-

- face at which it is supported on, and bodily rollable along, said support, and means operating automatically in timed relation to the movement of said bucket, to move said receptacle into a position for discharging its contents into said bucket when the latter is in charge-receiving position.
14. Material-elevating apparatus comprising, in combination, a hopper, a bucket for elevating the material, a support, a receptacle for receiving material from said hopper, for discharge into said bucket, said receptacle having a curved supporting surface at which it is supported on, and bodily rollable along, said support, and means operated by said bucket for actuating said receptacle.

15. Material-elevating apparatus comprising, in combination, a hopper, a bucket for elevating the material, a support, a receptacle for receiving material from said hopper, for discharge into said bucket, said receptacle having a curved supporting surface at which it is supported on, and bodily rollable along, said support, and means operated by said bucket for moving said receptacle to discharging position.

16. Material-elevating apparatus comprising, in combination, a hopper, a bucket for elevating the material, a support, a receptacle for receiving material from said hopper, for discharge into said bucket, said receptacle having a curved supporting surface at which it is supported on, and bodily rollable along, said support, means operated by said bucket for moving said receptacle to discharging position, and mechanism yieldingly resisting movement of said receptacle out of filling position and operative to return said receptacle to filling position.

17. Material-elevating apparatus comprising, in combination, a hopper, a bucket for elevating the material, a support, a receptacle for receiving material from said hopper, for discharge into said bucket, said receptacle having a curved supporting surface at which it is supported on, and bodily rollable along, said support, cable and weight mechanism for moving said receptacle toward receptacle-filling position, and means operated by said bucket for moving said receptacle toward receptacle-discharging position.

18. Material-elevating apparatus comprising, in combination, a hopper, a bucket for elevating the material, a support, a receptacle for receiving material from said hopper, for discharge into said bucket, said receptacle having a curved supporting surface at which it is supported on, and bodily rollable along, said support, means movably supported on said receptacle for directing the material from said receptacle into said bucket, and means operated by said

bucket for actuating said receptacle, said first-named means being operated toward receptacle-closing position by said bucket.

19. Material-elevating apparatus comprising, in combination, a hopper having an outlet, a bucket for elevating the material, a support, a receptacle containing an inlet for receiving material from said hopper outlet and an outlet, said receptacle presenting a curved surface at which said receptacle is supported on, and is bodily rollable along, said support, a device movably supported on said receptacle and controlling the outlet thereof, a movably supported gate device, means tending to move said gate device to a position in which it closes said hopper outlet, said gate device extending into the path of movement of said receptacle and being movable out of hopper-outlet-closing position by the movement of said receptacle in returning to filling position, and cable mechanism engaging said receptacle, said cable mechanism including a member which extends into the path of downward movement of said bucket and through the medium of which said receptacle is moved to discharging position, said cable mechanism including weight means operating to return said receptacle to filling position and said gate device to a position in which said hopper outlet is open in the upward movement of said bucket.

20. In material-elevating apparatus, the combination of a hopper having an outlet, a receptacle supported to receive material from said hopper through said outlet and movable away from said outlet to discharge position, a gate for closing said outlet, and means for yieldingly holding said gate in a position for closing said outlet, said gate extending into the path of movement of said receptacle and being movable thereby out of closed condition in the movement of said receptacle to a position for receiving material from said hopper, said gate automatically moving to closed position when said receptacle is moved out of material-receiving position.

21. In material-elevating apparatus, the combination of a hopper having an outlet, a receptacle supported to receive material from said hopper through said outlet and movable away from said outlet to discharge position and provided with a cutting edge which cuts through the material, a gate for closing said outlet, and means for causing said gate to move to closed position in the movement of said receptacle out of filling position, the parts being so constructed and arranged that the forward edge of the gate extends below said cutting edge and moves substantially in the same path as the edge of the receptacle which cuts through the material.

22. In material-elevating apparatus, the combination of a hopper having an outlet,

- a receptacle supported to receive material from said hopper through said outlet and movable away from said outlet to discharge position and provided with a cutting edge 5 which cuts through the material, a pivotally supported gate for closing said outlet, and means for causing said gate to move to closed position in the movement of said receptacle out of filling position, the parts 10 being so constructed and arranged that the forward edge of the gate extends below said cutting edge and moves substantially in the same path as the edge of the receptacle which cuts through the material.
- 15 23. In material-elevating apparatus, the combination of a hopper having an outlet, a receptacle supported to receive material from said hopper through said outlet and movable away from said outlet to discharge position, a gate for closing said outlet, and means for yieldingly holding said gate in a 20 position for closing said outlet, said gate

extending into the path of movement of said receptacle and being movable thereby out of closed condition in the movement of said receptacle to a position for receiving material from said hopper, said gate automatically moving to closed position when said receptacle is moved out of material-receiving position, the parts being so constructed and arranged that the forward edge of the gate moves substantially in the same path as the edge of the receptacle which cuts through the material.

24. In material elevating apparatus, the combination of a hopper, a support, and a receptacle engaging said support for receiving material from said hopper, said receptacle being mounted to be bodily movable along said support toward and away from said hopper and tilted into material-discharging position, said receptacle having separate filling and discharging openings.

BARTON S. SNOW.
